SELF-INKING HAND-STAMP.

1,132,519.

Specification of Letters Patent. Patented Mar. 16, 1915.

Application filed April 4, 1914. Serial No. 829,442.

To all whom it may concern:

Be it known that we, HARRY S. FOLGER and CASPER L. REDFIELD, citizens of the United States of America, and residents of Chicago, 5 county of Cook, and State of Illinois, have invented certain new and useful Improvements in Self-Inking Hand-Stamps, of which the following is a specification.

Our invention relates to self inking hand- 10 stamps and has for its object improvements in such stamps.

In the accompanying drawings Figure 1 is a side elevation; Fig. 2 is a front elevation; Fig. 3 is a central section corresponding 15 to Fig. 2; and Fig. 4 is an enlarged section on line 4—4 of Fig. 3.

In said drawings the type bands 10 are supported in a frame 11 provided with a handle 12. The bands 10 are supported on 20 band wheels 13 mounted upon a band shaft 14. At the lower part of the frame 11 the type bands run over a bridge 15.

The parts so far described represent the ordinary hand dating stamp well known in 25 the trade and require no further description.

Through the lower part of the frame 11, and just above the bridge 15, is a shaft 16 parallel to the shaft 14. The outer ends of shafts 14 and 16 are connected to links 30 17 and are guided in slots 18 in the side frames 19. Tie rods 20 secure the side frames 19 together below, while the parts associated with the shaft 16 hold the upper parts of the frames 19 so that said frames 35 will remain parallel and permit the stamp frame 11 to rise and fall in the frames 19.

Pivoted on screws 21 in side frames 19 is 40 a swinging frame 22 in which is supported a pad holding box 23. This box contains the ink pad 24. The pivot 21 is so located that when the band frame 11 is at its highest position and the swinging frame 22 is moved forward under the bands 10, the face of the 45 pad 24 will be in contact with the type on the bands which are directly beneath the bridge 15.

Secured to the shaft 16 by pins 25 are 50 arms 26 which have their free ends pivoted at 27 to the side arms of the swinging frame 22. These parts are so arranged that when the band holding frame 11 is moved downward in the side frames 19, the pad holding frame 22 will be moved from the position shown in full lines in Fig. 4 to that shown in 55 dotted lines. In this moving, the pad will

initially move downward more rapidly than the type, and then will move laterally out of the way so that the type may move past the pad to the printing point.

On the shaft 16 is a spring 28 having one 60 end secured to the shaft and the other end secured to the band frame 11. As the arms 26 are rigidly secured to the shaft 16 by the pins 25, and as the free ends of these arms swing rearwardly and upwardly in the arc 65 of a circle about the pivot 21 when the shaft 16 descends in the slot 18, it will be evident that such action turns the shaft 16 in its bearings and winds the spring 28. The wind of the spring 28 on the shaft 16, and its initial tension, are so arranged that the action 70 of the spring is to elevate the band holding frame 11. This elevation finds its limit by contact, between the pad 24 and the type 10, the connections being such that the pad is 75 moving upward more rapidly than the type at the instant of contact.

In using the stamp, the side frames 19 are stationary and the type carrying parts move 80 downward in these frames. In making such movement, the hand of the operator is brought toward the tops of the frames 19 which are on opposite sides of the handle 12. To avoid having the hand strike these frames and at the same time to keep the 85 handle short so that the entire stamp will not occupy too much space, the side frames do not extend far enough upward to inclose the shaft 14 in the slots 18 when the stamp is in normal position. This leaves the slots 90 18 open at their upper ends. To properly guide the stamp body in the side frames at the beginning of the downward movement of the body, guide blocks 29 are secured to the inside of the links 17 and operate the 95 slots 18. These blocks 29 may extend the entire length of the links 17 and serve as the only guides for the stamp body in the frames 19. We have, however, shown them simply as short blocks located between the 100 shafts 14 and 16, the said shafts themselves serving as the ends of the guides in the slots 18.

It will be observed that the stamp frame composed of the plates 19 is not symmetrical with regard to the center line of the slots 18, but extends farther to the rear than to the front of the center line of the stamp. The object in shortening the forward extension of the frames 19 to something less 110

than would be normally used for a substantial base is to bring the front tie rod 20 near to the type when in printing position so that said rod will serve as a visual guide in 5 placing the stamp accurately at the place where it is desired that the printing shall be. The rearward extension is made somewhat more than it would otherwise be for the purpose of compensating for the shortening 10 in front and thereby giving it the desired substantial base. The parts above the base are so distributed that the center of weight will fall to the rear of the center line of the stamp body and near the center of the 15 base of the frames 19.

Referring back to that part of the description which states that as the shaft 16 (and consequently the stamp body) moves downward in the side frames 19 the pivots 27 20 move in the arc of a circle about pivots 21, it will be seen by the inspection of Fig. 4 that the shaft 16 not only moves below pivots 21 but also below moving pivots 27. The effect of this is to bring the rearward movement of the pad 24 to a stop while the type are moving downward and to also give it a very slight forward movement just as the type are reaching the printing point. The 25 general result of this is to reduce the total movement of the pad to a minimum and thereby save space in the stamp and power required to move the stamp body and pad in the printing action.

In one of the links 17 is a notch 30, and 30 secured to the adjacent frame 19 is a dog 31, adapted to engage said notch when the stamp is nearest its lowest position and hold it in that position, against the elevating action of the spring 28. The notch 30 and dog 31 are so related that when in engagement 35 with each other the pad 24 is at or near its most rearward position. The pad box 23 is held in the swinging frame 22 by friction and may be pushed out of the frame 22 by 40 the application of a moderate force manually applied. By the chain of connections involving the vertical descent of the stamp body and the movement of the pad to its most rearward position at a time when the 45 stamp body is near but somewhat above its lowest position, the notch 30 and dog 31 serve to hold the swinging frame 22 in that position in which it is most easy to remove the pad box for inking the pad. The rearward extension of the frame 19 which places the rear tie rod 20 farther from the center of the stamp movement than is the front tie rod gives convenient space for the downward movement of the pad box to release it 50 from the swinging frame. This held position of the swinging frame and pad box is somewhat to the rear of the dotted position shown in Fig. 4, which dotted position is that occupied when the stamp body is at its 55 lowest position.

It will be observed that the connections for self inking are located between the stamp frame 11 and the side frames 19, and consequently are protected from injury, even when the stamp is subjected to such 70 accidents as falling upon the floor. Also, that the elevating spring 28 is concealed behind the bands 10 and gives no exterior evidence of its existence. Placing the elevating spring at this place between the band wheels 75 13 and the bridge 15 avoids the necessity for a long handle to receive such spring as is the case with ordinary self inking stamps.

It is to be observed that the two side frames 19 are flat plates exactly alike and 80 are connected together by tie rods. By simply changing the length of these tie rods and the pad holding devices, the same frames and operating devices are adapted to accommodate stamps of any width. 85

The term "dating stamps" as used in the claims hereinafter refers to a complete device which is not self inking but which is adapted for ordinary hand usage without any of the attachments which adapt it to self inking operations. It is the complete 90 commercial article to which self inking attachments are applied.

Dating stamps are usually band stamps, and that form of dater is here illustrated. 95 Band stamps are sometimes numbering stamps by reason of changes in the characters on the bands, but "dating stamps" as here used is intended to include band stamps of the character illustrated in the 100 drawings.

What we claim is:

1. A frame consisting of two sheet metal plates connected together by tie rods, a hand stamp located between the frame plates, projections on the stamp projecting through slots in the frame plates, and guide plates 105 17 secured to the outer faces of said projections and bearing against the outer faces of the frame plates to guide the stamp when 110 reciprocated in the frame.

2. The combination with a hand stamp comprising type band, band wheels, a containing frame and a handle by which the stamp may be used as a hand inker, of an 115 outer frame consisting of two sheet metal plates located on opposite sides of the stamp, tie rods connecting the two plates together, an ink pad pivoted to the outer frame, links pivoted to the stamp and connected to the 120 pad, and a stamp elevated spring mounted upon the pivotal supports for the links.

3. A frame consisting of two sheet metal side plates connected together by tie rods, a stamp located between the plates and guided 125 by the outer faces of said plates, a pad pivoted to the side plates, and a pad-moving link connected to the stamp between the stamp body and the outer guides therefor.

4. The combination with the frame, the 130

- type bands and the band wheels of a dating stamp, of an outer frame consisting of two plates, tie rods connecting said plates, a wheel supporting shaft in the stamp frame 5 and extending each side beyond the outer frame, a second shaft in the stamp frame and also extending beyond the outer frame, links connecting adjacent ends of the said shafts and guided in slots in the outer frame, 10 and a spring located on the second shaft and serving to elevate the stamp frame in the outer frame.
5. The combination with the frame and type bands of a hand stamp, and an outer frame in which the stamp is vertically guided, of an ink pad pivoted to the outer frame, a shaft extending through both frames and the space inclosed by the type bands, an elevating spring on said shaft 15 within said space, and links connecting the ink pad to the parts of the shaft between the inner and outer frames.
6. The combination with a band stamp, of a frame within which the stamp is guided, 20 a shaft extending through the stamp and frame, an elevating spring located on said shaft and within the stamp, an inking pad, and connections from the pad to those parts of the shaft between the stamp and the frame.
7. The combination with "a dating stamp" of a frame having guiding slots therein, links connected to the "stamp" and provided with guide blocks operating in 25 said guiding slots, and a dog secured to the side of the frame and adapted to engage a notch in one of said links to hold the "stamp" at a fixed place in the frame.
8. The combination with "a dating 30 stamp", of a frame consisting of separate plates located on opposite sides of the
- "stamp" and connected together by tie rods, links connected to the "stamp" and located outside of the plates forming the frame, means by which the "stamp" may be reciprocated in the frame, and a dog secured to the outside of one of said plates and adapted to engage a notch in the adjacent link to hold the "stamp" at a fixed place in the frame. 45
9. A stamp body, a stamp frame within which the body reciprocates, a swinging frame pivoted to the stamp frame, an ink pad supported in the swinging frame, a shaft extending through the stamp body, 50 links rigidly secured to the shaft and pivotally connected to the swinging frame, and a spring located upon said shaft and acting to turn the same so as to bring the pad against the stamp body. 55
10. A stamp frame, a stamp body arranged to reciprocate in the stamp frame, a swinging frame pivoted to the stamp frame, a removable ink pad supported in the swinging frame, a shaft extending through the stamp body, links rigidly secured to opposite ends of the shaft and pivotally connected to the swinging frame, a spring on said shaft and acting to hold the pad against the stamp body, and locking devices for holding the swinging frame with the pad away from the stamp body and in a position convenient for the removal of the pad. 60
